UNITED STATES PATENT OFFICE.

HOWARD R. SARGENT, OF SCHENECTADY, NEW YORK, ASSIGNOR TO GENERAL ELECTRIC COMPANY, A CORPORATION OF NEW YORK.

TWIN LAMP-SOCKET.

960,414.

Specification of Letters Patent.

Patented June 7, 1910.

Application filed August 21, 1909. Serial No. 513,918.

To all whom it may concern:

Be it known that I, HOWARD R. SARGENT, a citizen of the United States, residing at Schenectady, county of Schenectady, State of New York, have invented certain new and useful Improvements in Twin Lamp-Sockets, of which the following is a specification.

This invention relates to incandescent electric lamp fixtures, and its object is to provide a simple and inexpensive device for holding two lamps, with their filaments connected in multiple.

The invention consists of a stand or base of insulating material, having secured to its middle a metallic bracket to which the screwthreaded shell contacts are fastened, preferably in alinement, and extending in opposite directions therefrom, with their outer ends resting upon upright blocks at the ends of the base. Each shell has a jacket of insulation. A metallic standard, secured to the base, extends through a hole cut in the adjacent sides and ends of said shells and affords a center contact for both receptacles.

25 The bracket and the standard have feet in which binding posts are inserted. A removable trough-shaped cover fits over the shells and extends down to the base, having notches in its lower edges for the passage 30 of the line wires to the binding posts.

In the accompanying drawing, Figure 1 is a longitudinal section of my improved twin lamp socket. Fig. 2 is an end elevation of the same. Fig. 3 is a side elevation showing the cover lifted off. Fig. 4 is a perspective view of the bracket, and Fig. 5 is a similar view of the standard.

The base 1 is composed of molded insulating material, preferably porcelain. At 40 each end it has an upright block 2 whose top is cut out on a circular arc concentric with the end of a screwthreaded metallic shell 3.

The two shells are arranged with their axes in line and parallel with the base 1. Each 45 shell is incased in a jacket 4 of fiber or other insulating material. The adjacent inner ends of the shells abut against an upright metallic bracket 5, which has a foot 6 secured to the base 1, and a curved portion 7. The bottom flanges of the two shells abut 50 against opposite sides of said curved portion, to which they are attached, preferably by means of rivets 8 passing through both flanges and said intervening portion 7 of the bracket. The adjoining bottoms and side

walls of the shells, together with the jackets, are cut away on one side, forming an opening through which a metallic standard 9 extends into the two receptacles. This standard has at its upper end two ears 10 which lie in the common axis of the two shells and form the center contacts. The standard has a foot 11 secured to the base, and in each of the feet 6 11 is a binding screw 12.

A trough-shaped cover 13 of molded insulating material slips on over the shells and rests on the base 1. It can be fastened conveniently by a screw 14 engaging with a tapped hole in a right-angled arm 15 rising from the bracket 5 above the shells and preferably received in a recess in the cover. The lower edges of the cover have notches 16 to permit line wires to enter and reach the binding posts. Or, if desired, said wires 75 may be carried in through holes 17 in the base.

This socket for holding two lamps is simple in construction, the base and cover being easily molded, and the metal parts being 80 few. The screw shells are of standard make, and the bracket and the standard are punchings which can be quickly bent into shape. The two shells are supported by the bracket 5, to which also the cover is attached. The 85 cover is prevented from shifting endwise by means of its recesses 18 fitting over the feet 6 11.

In accordance with the provisions of the patent statutes, I have described the principle of operation of my invention, together with the apparatus which I now consider to represent the best embodiment thereof; but I desire to have it understood that the apparatus shown is only illustrative, and that 95 the invention can be carried out by other means.

What I claim as new and desire to secure by Letters Patent of the United States, is:

1. A twin lamp socket comprising a base 100 provided with upright blocks at its ends having their tops cut out on a circular arc, a bracket secured to said base, having a foot provided with a binding screw, a curved portion and a right-angled arm at the top, 105 two screw threaded metallic shells having a common axis parallel to said base, and provided with bottom flanges abutting against said curved portion and riveted thereto, said shells being cut away on one side to 110

form an opening, a standard secured to said base and extending up through said cutaway opening and having ears in line with the common axis of said shells, insulating jackets on said shells, and a trough-shaped cover fitting over said shells and attached to the arm on the bracket, said cover being notched to admit the line wires.

2. A twin lamp socket comprising a base 10 having upright blocks, a bracket secured to said base having a foot provided with a binding screw and having also a curved portion, two screw shells abutting against opposite sides of said curved portion and attached 15 thereto, and having an opening in one side, a standard secured to said base and extending through said opening, and a trough-shaped cover fitting over said shells and attached to the upper end of said bracket.
- 20 3. A twin lamp socket comprising a base, a bracket secured thereto and having a foot provided with a binding screw, two screw

shells abutting against opposite sides of said bracket and attached thereto, a standard secured to said base and projecting through 25 an opening in said shells, and a trough-shaped cover inclosing said shells.

4. A twin lamp socket comprising a base, a bracket thereon, two screw shells supported by said bracket and having an opening 30 in one side, and a standard projecting through said opening and forming the center contact for the two receptacles.

5. A twin lamp socket comprising a base, two aligned screw threaded shells parallel 35 therewith, and a trough-shaped cover fitting over said shells.

In witness whereof I have hereunto set my hand this 19th day of August 1909.

HOWARD R. SARGENT.
